APPARATUS FOR CASTING HOLLOW METAL ARTICLES

John Pinkney Gowland, Woking, England

Application February 9, 1943, Serial No. 475,273
In Great Britain February 10, 1942

5 Claims. (Cl. 22—57)

The present invention relates to apparatus for casting hollow metal articles, and more particularly to casting hollow metal articles, such as toy soldiers and similar figures, in lead alloys and the like.

In the conventional apparatus employed for casting hollow toy soldiers and other figures, a split mould is used the two halves of which are carried respectively by a pair of pivoted arms in the form of tongs of the nutcracker type, the arms being closed to bring the two mould halves together for casting and being opened for ejection. On one of the mould halves is pivotally mounted a cutter plate in the form of a lever which carries a cup or funnel and which can be swung about its pivot so as to bring the funnel into alignment with the aperture or gate in the join between the mould halves. In using such apparatus the tongs are closed, the cutter plate is shifted until the funnel is in alignment with the gate, and the molten metal poured into the funnel. The hinged end of the tongs is rested against a supporting block and after the metal has been poured the tongs carrying the mould are swung upwards and over about the hinged end resting on the block until the funnel is inverted so as to decant the surplus molten metal in the mould, leaving only a thin skin of metal in the mould which has been chilled against the comparatively cold mould. The cutter plate is then swung about its pivot to shear the flash on the base of the figure, whereafter the mould is opened by opening the tongs and the casting removed.

With the conventional apparatus the tongs must be held by hand and the operator generally has to stand in order to be able to swing over the tongs and mould from one position to the other. The heavier the mould the harder the work, and female labour can in general operate only small moulds.

An object of this invention is the provision of improved casting apparatus of the character above mentioned which will have advantages in increasing the speed of casting. Another object is the provision of casting apparatus which will be easier and less fatiguing to handle than similar apparatus known heretofore and which will enable heavier classes of work to be handled satisfactorily by female labour. A further object is to accelerate the rate of production of hollow cast articles by the provision of apparatus enabling a plurality of such articles to be cast simultaneously.

In the accompanying drawing

Fig. 1 is a plan view of a preferred form of casting apparatus embodying the invention;

Fig. 2 is a section on line 2—2 of Fig. 1;

Fig. 3 is a side view of the apparatus of Fig. 1 showing it in association with metal feeding means; and

Fig. 4 is a perspective view of a modification.

Whereas in the conventional casting apparatus previously mentioned the mould-carrying tongs were arranged to swing in a vertical arc about a transverse horizontal axis at one end of the tongs, a feature of my invention consists in eliminating such arcuate swing by mounting the mould-carrying mutually separable members of a casting apparatus so as to revolve as a unit on a horizontal longitudinal axis of the unit. As seen in Figs. 1 to 3, the apparatus therein illustrated comprises a base plate 10 for attachment of the apparatus to a workbench or other suitable supporting surface, and upstanding from the plate 10 is a pair of aligned bearing brackets 11, 12 which support the mould-carrying members of the apparatus. These members comprise a rectangular frame denoted generally by the reference numeral 14, and a plate or bolster 15 on which are removably fixed the two halves 13a, 13b of a longitudinally split mould. The mould in the example shown is constructed for obtaining multiple castings simultaneously by arranging the multiple impressions 16 (Fig. 2) in line in the common mould. The side 17 of the frame 14 and the bolster 15, are adapted in convenient manner to have the mould sections 13a, 13b fixed there-

to respectively, for instance by set screws 18. The bolster 15 is formed at its ends with eyes 19 which are slidable respectively on guide rods 20 passing therethrough transversely of the frame 14 and secured to the opposite sides 17 and 21 of the frame by nuts 22 threaded on the projecting threaded ends of the guides 20. Compression springs 23 encircling the guides 20 and bearing between the inner face of the frame member 17 and the opposing faces of the eyes 19 tend to urge the bolster 15 away from the member 17 and thus to urge the mould sections 13a, 13b apart. A bell crank lever 24, pivoted by a pivot pin 25 between a pair of outwardly directed parallel lugs 26 on the frame member 21, has its shorter arm passing through an aperture in the member 21 and carrying a roller 27 in engagement with the bolster 15. The lever 24 when in the position shown in Fig. 1 keeps the mould closed, and when swung outwardly allows the springs 23 to displace the bolster 15

and thereby open the mould. At one end 28 remote from the lever 24 the frame 14 is provided with a spigot 29 which lies on the longitudinal axis of the frame 14 and is journaled in the bearing bracket 11. At the opposite end 30 of the frame 14 a spindle 31 is provided aligned with the spigot 29 and journaled in the bearing bracket 12. The spindle 31 passes through the bracket 12 and is fitted at its free end with a handle 32. The free end of the lever 24 is similarly provided with a handle 33 and is set inwards in crank fashion at 34 so as to bring the handle 32 and 33 together and facilitate their being held in one hand.

A further feature of the invention consists in eliminating the movable cutter plate heretofore employed in the conventional apparatus, and with the elimination of the cutter plate to fit the funnel that was carried by such plate, directly upon the mould itself, the funnel for this purpose being split into a plurality of sections corresponding to the splitting of the mould and the funnel sections being secured to the respective mould sections so that when the latter are held together to form the closed mould the funnel sections fit together to form the complete funnel. Thus, with a multiple-impression mould as illustrated, there is provided a set of funnels associated one with each gate 35 in the mould. The set of funnels is split into two halves 36a, 36b corresponding to the division of the mould 13a, 13b and all the funnel halves 36a or 36b carried by each half 13a or 13b of the mould are preferably made in one piece which is secured to the corresponding mould section in any convenient fashion, as by screws 37 or by hinging thereto so as to hinge away from the split, so as to facilitate removal of the castings.

In using the apparatus described molten metal may be ladled into each of the funnels but preferably for faster working, provision is made for feeding all the funnels simultaneously. Such provision may be of the form illustrated in Fig. 3 where the apparatus is shown associated with a duct 38 carrying molten metal from a melting pot 39, the duct being disposed longitudinally over the funnels and having a set of nozzles 40 placed to deliver molten metal to the respective funnels. The duct 38 is provided with a suitable valve device for regulating the supply of metal to the funnels, such device preferably operating simultaneously on all the nozzles 40. For this purpose, the valve device may comprise an apertured slide bar 41 disposed longitudinally within the duct 38 and overlying the nozzle apertures, the bar 41 being connected with a spring-loaded hand plunger 42 outside the duct, by means of which the bar can be displaced by pressing the plunger so as to bring the apertures 43 in the bar in register with the nozzle apertures and thereby permit flow of metal through the nozzles. The plunger 42, when released, is restored by action of its spring 44 to bring the apertures 43 in the bar 41 out of register with the nozzle apertures and thereby cut off the metal flow.

After the metal has been poured into the mould it is necessary only to apply a hand twist to the handles 32, 33 to revolve the frame 14 on the bearing brackets 11, 12, to invert the mould and thus decant the surplus metal, after which the mould is opened by swinging the lever 24 outwards, which simultaneously separates the funnel sections attached to the mould sections, and the castings can then be removed by hand or by ejectors. Any flash occurring at the base of the

castings may be easily removed in a separate shearing operation.

It will be clearly appreciated that the brackets 11, 12 bear the whole weight of the rotatable parts of the apparatus, thus facilitating the work and enabling female operators to operate even the heaviest moulds. Because the construction of the apparatus relieves the operator of the weight when turning over the mould, it is a practical proposition to construct moulds for multiple impressions of substantial number. By ensuring that the revolving unit is well balanced, if necessary providing a balance weight on the frame member 21, the minimum of effort will be required to turn the mould over.

It is not essential in all cases that the mould-carrying turnover unit be supported at both ends, as it may be quite sufficient, for example with small moulds, to support the unit at one end only. As an illustration of this, attention is directed to the modification illustrated in Fig. 4 in which the turnover unit is supported at one end by an angle bracket 50 which is adapted to be secured to the workbench or other supporting surface. The turnover unit comprises a pair of tongs formed of two arms 51, 52, the arm 52 of which is L-shaped and the other arm 51 is substantially straight, the end of the arm 51 being hinged to the free end of the short portion of the arm 52 by the hinge 53. At the centre of the short portion of arm 52 is secured a spigot 54 which extends axially of the tongs and passes through a bearing hole in the bracket 50, the spigot 54 being rotatable in the bracket and held against being pulled out therefrom by a nut 55 or equivalent stop secured on the portion of the spigot which projects through the bracket. The two arms 51, 52 of the tongs are adapted for carrying the respective halves 55a, 55b of a mould secured thereto by screws 56. These mould halves carry in a manner similar to that described in the previous embodiment the two halves 57a, 57b of a set of funnels corresponding in number to the number of impressions provided in the mould. The free ends of the arms 51, 52 are formed or provided with handles 58, 59 and may be stepped inwards in crank fashion, if necessary, so as to bring the handles sufficiently close together to be easily held in one hand. The mould is kept closed by holding these handles together. When molten metal has been poured into the mould it is necessary only to rotate the tongs about the axis provided by the spigot 54 to pour out the surplus metal. The bracket 50 bears the weight of one end of the unit, and if the bearing is made sufficiently long can actually be arranged to bear the whole weight of the unit. The positioning of the spigot 54 at the centre of the short portion of the arm 52 gives good balance to the unit which thus needs little effort to turn it over.

Consideration of the foregoing will it is believed demonstrate that the invention has provided improvements in casting apparatus enabling the rate of production of castings to be increased through the apparatus being easier, quicker and less arduous to handle, such improvements further enabling multiple castings to be made simultaneously. It will be evident, however, that the improvements which make this production of multiple castings practicable are also useful with like advantages for moulds with single impressions. Further, the improved turnover arrangement is applicable with advantage to moulds furnished with a cutter plate and attached funnel

as heretofore practised. It will also be apparent that the improved apparatus is readily adaptable to operation mechanically, as well as by hand.

I claim:

1. Apparatus for casting hollow metal articles, comprising a rectangular frame, a pair of spaced apart aligned bearing brackets, said frame being positioned between said brackets with opposite ends of the frame adjacent said brackets respectively, means on said frame ends supporting said frame rotatably in said brackets, a pair of guides within said frame adjacent the respective ends thereof and extending transversely of the frame between the opposite sides thereof, a bolster slidably mounted on said guides, said bolster and one of the sides of said frame being adapted for carrying the component sections of a split mould thereon respectively, spring means on said guides between said bolster and said mould-carrying side of said frame, said spring means acting to urge said bolster and side apart, lever means pivoted to said frame and acting on said bolster against the action of said spring means, said lever means being adapted to lock said bolster in mould-closing position, said frame and said lever means having handles adapted to be mutually juxtaposed when said lever means is in mould-closing position whereby said handles may be collectively held in one hand.

2. Apparatus for casting hollow metal articles comprising a mould assembly constituted by the combination of a mould having a plurality of impressions of the article to be cast arranged in line longitudinally in the mould, and a set of funnels arranged in line respectively over the gates of said mould impressions and attached to the mould, said assembly being split longitudinally into a plurality of combined mould and funnel sections, a plurality of co-acting mutually separable members carrying said sections, means mounting said section-carrying members to revolve as a unit on an axis longitudinally of the unit, whereby said unit is turnable from a casting position to a turned-over position for decanting surplus metal from the mould, and means including a set of nozzles and flow-regulating means for supplying molten casting metal to all said funnels simultaneously, said nozzles being located in line above said unit so as to be vertically above said funnels respectively when said unit is in casting position.

3. Apparatus as defined in claim 2, said supply means also including a duct carrying said nozzles branching therefrom and externally controllable valve means within said duct and associated with said nozzles to regulate metal flow through all said nozzles simultaneously.

4. In apparatus for tip-casting toy figures and like hollow metal articles that are cast with a baseplate on which to stand, the combination of a coreless split mould comprising a pair of complementary separable mould sections containing an inverted impression of an article and included baseplate to be cast so that the baseplate portion of the impression is uppermost and contiguous with the upper face of the mould, a separable funnel over the gate of the mould impression comprising a pair of complementary funnel sections on the upper face of the respective mould sections so as to be separable therewith, the portion of the underface of said funnel which overlies the mould impression defining the inverted underface of the baseplate portion of said impression, each funnel section being secured to the underlying mould section by means capable of permitting upward play of the funnel section relatively to the underlying mould section for facilitating withdrawal of the funnel section from the baseplate of the casting, and means pivotally supporting said mould for inversion by revolution.

5. In apparatus for tip-casting toy figures and like hollow metal articles of the kind having a cast baseplate on which to stand, the combination comprising a coreless mould containing longitudinally therein a line of inverted impressions of the articles and included baseplates to be cast so that the baseplate portions of the impressions are uppermost and contiguous with the upper face of the mould, and a line of as many funnels as there are mould impressions arranged on the upper face of the mould over and communicating with the respective gates of the mould impressions, said line of funnels being separate from said mould and the portions of the underfaces of said funnels which overlie the respective mould impressions defining the inverted underfaces of the baseplate portions of said impressions, said assembly being split longitudinally into a pair of combined mould and funnel sections, means mounting said combined sections for relative mutual displacement to open and close the same, means securing the funnel sections of each combined section to the underlying mould section thereof, said securing means being capable of permitting upward play of the funnel sections relatively to their underlying mould section for facilitating withdrawal of the funnel sections from the baseplates of the castings, and means pivotally supporting said mould for bodily revolution on an axis longitudinally of the mould to invert the same.

JOHN PINKNEY GOWLAND.
